UNITED STATES PATENT OFFICE.

FRANK BEU, OF CHICAGO, ILLINOIS, ASSIGNOR OF ONE-FOURTH TO WILLARD M. McEWEN, OF CHICAGO, ILLINOIS.

OIL-BURNER.

1,393,937.

Specification of Letters Patent. Patented Oct. 13, 1921.

Application filed February 12, 1920. Serial No. 358,063.

To all whom it may concern:

Be it known that I, FRANK BEU, a citizen of the United States, residing at Chicago, in the county of Cook and State of Illinois, 5 have invented new and useful improvements in Oil-Burners, of which the following is a specification.

This invention relates to an oil burner.

Among the objects of my invention is to 10 provide an oil burner of such a construction that it may be incorporated in or applied to a steam boiler furnace and be used to produce the heat required to generate steam in the place of coal or other like combustible material heretofore used for that purpose. A further object of my invention is to generate the combustible gas from the oil used as the fuel at a point beyond the pipe or pipes carrying the oil to the place of gas 15 generation, and further keep said pipes relatively cool to avoid converting the oil while in the pipes into a gas and thus prevent the deposit of carbon in the pipes, so that the pipes will not become blocked to hinder the flow of oil therethrough. Another object of my invention is to supply air to the place where the oil is discharged from the pipes, so that the oil may be converted into a gas and be mixed with the oil vapor to produce a 20 combustible mixture, which when ignited gives the heat required to work the furnace.

The invention consists further in the matters hereinafter described and more particularly pointed out in the appended claims.

35 In the accompanying drawings—

Figure 1 is a side view of a steam boiler furnace and showing applied thereto an oil burner constructed in accordance with my invention;

40 Fig. 2 is an enlarged horizontal sectional view taken on the indirect line 2—2 of Fig. 1;

Fig. 3 is a top plan view taken on line 3—3 of Fig. 1;

45 Figs. 4, 5, and 6 are vertical sectional views taken on lines 4—4, 5—5, and 6—6, respectively, of Fig. 1; and

Fig. 7 is a vertical sectional view taken on line 7—7 of Fig. 2 to show a detail of construction.

In the drawings I have shown an oil burner of my invention applied to a steam boiler furnace of a well known type. The oil burner extends into the fire box of the 55 furnace and is used to heat the boiler to gen-

erate steam in place of and as a substitute for coal or other like combustible material heretofore used for that purpose.

The steam boiler furnace illustrated is of that type comprising two side walls 1, 1 built upward from a suitable foundation 2, which not only supports the furnace structure but forms the floor of the ash pit. Located between the side walls is a steam boiler 3 horizontally arranged, or substantially so, and of that kind having a plurality of flues 4, 4 extending therethrough from end to end, as shown. The forward end of the boiler 3 rests on the front wall 5 of the furnace setting, and the flues 4 open at that end into a smoke chamber 6 communicating with a stack or chimney 7, as customary. The boiler 3 is further supported by the side walls, and its rear end terminates short of the rear wall 8 of the furnace setting, as shown in Fig. 1, to allow the heated gases produced in the fire box to enter the flues at the rear after traveling along the under side of the boiler. The side walls 1, 1 are continued upward over the top of the boiler to completely house the same, as shown. Extending between the side walls 1, 1, beneath the boiler 3 and at a point intermediate the ends thereof, is a bridge wall 9 rising upward from the foundation 2. This wall 9 terminates short of the boiler 3 to permit the heated gases produced in the fire box to pass over said bridge wall toward the rear end of the boiler; the fire box being in front of the bridge wall, as customary. I have merely shown enough of the furnace structure to illustrate the application thereto of my oil burner.

An oil burner of my invention, when applied to a steam boiler furnace of the type shown, is constructed as follows. In applying the burner, the grate bars of the furnace are removed from the fire-box, and the ash pit is filled with a suitable material, such as concrete 10, to form a base for supporting those parts of my burner structure located in the fire-box. The base 10 is given the height desired, as for example the height that the grate bars were above the floor of the ash pit. On the base 10 are built two upright walls 11, 12, of the same height and spaced apart laterally. The walls are preferably made of fire brick or other refractory material and are given the thickness desired. The walls 11, 12 are of course in the fire-box.

and extend from the front wall 5 to a point short of the bridge wall 9, as shown in Fig. 2. Said walls 11, 12 have their inner end portions 13, 14 diverging so as to be spaced 5 apart a greater distance than the remaining portions of the walls to form chambers, to be hereinafter referred to more in detail. Substantially midway between these wall portions 13, 14, there is built on the base 10 10 an upright partition wall 15, also of fire brick or suitable refractory material and preferably of a double thickness. This wall 15 extends to the bridge wall 9, its front end portions 16, 17 diverging to meet the inner 15 ends of air pipes or conduits 18, 19 between the walls 11, 12. The air conduits 18, 19 are inserted into the fire-box of the furnace through the fire door opening 20 provided in the front wall 5 of the furnace. The pipes 18, 19 are supported in place by having them 20 incased in fire brick 21 built in said opening, the fire door of the original furnace structure being removed to permit this to be done. The pipes 18, 19 are substantially 25 parallel and extend beyond the front wall of the furnace, as shown. Each conduit 18, 19 is connected at its outer end with the outlet or discharge of a blower 22, there being a blower for each pipe. The blowers are 30 operated by any form of prime mover, as electric motors 23, there being, in the particular construction shown, a separate motor for each blower. The blowers could be operated by one motor if desired, as by connecting the shafts of the blowers together, but a separate motor for each blower is 35 preferable so that all the blowers will not be rendered inoperative in case any one of the motors fails for any reason. Thus, that 40 part of the burner connected with the blower still operative could be used to heat the boiler and generate steam until the faulty motor is repaired or replaced by a new one. The blowers and motors are 45 mounted on a suitable support or foundation 24 built for that purpose in front and outside of the furnace setting. The inner ends of the pipes 18, 19 terminate on opposite sides of the partition wall 15 and open 50 into chambers 25 formed in part by said partition wall and the walls 13, 14. Thus, by said pipes 18, 19, the blowers may discharge or deliver air into such chambers, and to regulate the amount of air delivered 55 into the respective chambers there is a manually operable slide valve or gate 26 in each pipe 18, 19, as shown in Fig. 2.

To complete the chambers 25, there is built inward from the bridge wall 9 two 60 arches 27, 27, one extending from the partition wall 15 to one of the side walls 1, and the other arch extending to the other side wall, as clearly shown in Fig. 5. These 65 arches form a roof or top wall for their respective chambers 25, and the outlets 28,

therefrom open toward the respective side walls 1, 1 of the furnace setting; the walls 13, 14 terminating short of the bridge wall 9 for that purpose. These walls 13, 14 extend upward to the arches, as shown, so that 70 there is only one outlet 28 for each chamber 25.

A liquid fuel is used with the burner, this being an oil supplied to the burner from a tank 29, located at any convenient point outside of the furnace setting and supported at an elevation to give a gravity feed, as shown in Fig. 1. This oil may be of a heavy body kind, as crude oil, and is led from the tank by a pipe 30, extended to and across the 80 front of the furnace setting, as shown in Figs. 1 and 2. The pipe 30 extends across and over both of the air pipes 18, 19, and has two branch pipes 31, 32. The pipe 31 leads down into the air pipe 18 in advance of the place where that pipe enters the furnace setting, and is continued by a pipe 33 through the air pipe 18 to the inner end thereof, where it opens into the chamber 25 at the inner end of said air pipe 18. The 90 other pipe 32 leads, in a like manner, into the air pipe 19 and is connected with a pipe 34, which extends through the pipe 19 and opens into the other chamber 25. To completely shut off and control the supply 95 of oil to the pipes 33, 34, a hand valve 35 is located in the pipe 30 in advance of its connection with its branch pipes 31, 32. Each branch pipe 31, 32 has a hand valve 36, so that the oil supply thereto may be cut off 100 or controlled independently of the other branch pipe. Thus either side of the burner may be used independently of the other, or both sides may be used at the same time, and the supply of oil controlled to meet the 105 working conditions of the boiler.

To add water vapor to the oil supplied to the burner, there is a steam pipe 37 leading from a suitable source of supply, as for instance the steam boiler being heated by the 110 oil feed to the burner. This pipe 37 is extended to the front of the furnace setting and is provided with two branch pipes 38, 38, in each of which is a hand valve 39. There is a branch pipe 38 extending into each of the 115 fuel pipes 31, 32, and has its end opening and discharging into that portion of the fuel pipe 33, 34 which extends along inside of the air pipe 18 or 19, as shown in detail in Fig. 7.

The masonry 21 built in the fire door opening 20 may be covered on the outside by a plate 40, and the air pipes 18, 19 extend through this, as shown in Fig. 6. This plate is also provided with peep openings normally closed by hinged covers 41. These openings register with passages provided in the masonry 21, and there is one of such openings for each side of the burner so that the operator may have access into the 130

combustion chamber of the furnace for starting the burner and also to note the operation of the same from time to time. To inclose the air pipes 18, 19 in a chamber, the side walls of which are formed by the walls 11, 12, these walls are bridged above the pipes by a top wall 42, as particularly shown in Fig. 5. To aid in supporting these pipes and also to keep the temperature reduced as much as possible, the chamber formed by these walls is filled with a packing of loose sand 43, and a wall is built across this chamber at the inner ends of said air pipes to keep the sand from entering the chambers 25.

As shown in Fig. 7, the fuel pipe 32 is formed in part between the pipe section 34 and the valve 33 by a T-coupling 44 and a pipe section 45. To this coupling 44 is connected a pipe section 46 extending above the same and through which the branch 38 of the steam pipe extends. To the pipe 46 is connected a fitting 47 having a screw plug 48, which when removed permits access to be had into the pipe sections 45 and 34. The purpose of this is to permit a flexible feed pipe, or feed wire (not shown) as it is sometimes called, to be inserted into the fuel pipe at the time the burner is to be started. The other branch pipe 31 is provided with a like construction for the same purpose.

To start the burner, when incorporated in a steam boiler furnace of the type shown, the valves are closed. The blowers 22 are started and air discharged into the chambers 25. A flexible pipe or feed wire connected with a tank of more volatile oil, such as kerosene, is inserted into one of the pipes 31, 32 through the opening provided by removing the plug 48. For example, I will take the pipe 32 for the description in this connection, it being of course understood that the same method of starting will be used for the other side of the burner, after one side has been started. The feed wire is pushed into the pipe until the chamber 25 is reached. The kerosene being under pressure is discharged into this chamber and atomized by the air being forced into the same through the pipe 19. The kerosene is vaporized and mixed with the air in the chamber 25 and forms a combustible mixture, which flows or is forced by the incoming air out through the passage 28. The operator then opens the peep hole adjacent the pipe 19 and inserts into the fire-box of the furnace a bar or rod carrying a flame at its inner end, and when the flame reaches a proximity to the outlet passage 28 of the particular chamber 25, the combustible mixture formed in that chamber is ignited. Then the oil being used as fuel is turned on to this particular chamber and fed thereto by gravity. The air being discharged into the chamber from the end of the pipe 19 has sufficient force to draw the oil from the pipe 34, and the oil is not only

atomized or sprayed by this action, but is evaporated by the air to form a combustible mixture, which as soon as it strikes the heated area of the chamber about and adjacent the outlet passage 28 thereof ignites and produces a flame, thus producing the required heat to generate steam in the boiler 3. When the other side of the burner is in operation, both valves are then opened and the oil fed to both chambers 25. The generation of gas in both chambers is the same, and the two working in conjunction heat the boiler. The heated gases thus produced are forced out of the chambers 25 through the outlet passages 28 and up and over the arches 27 and along the under side of the boiler to the rear and then through the flues to the stack.

The point of ignition of the gaseous mixture, in each chamber 25, is at the rear thereof, that is, where the mixture strikes the walls and is deflected out of its straight path of movement. This being beyond the inner ends of the air pipes 18, 19 and their fuel pipes 33, 34, these pipes are removed from the direct action of the heat produced upon the ignition of the mixture. It is in this space that the air and oil mix, or, in other words, where the generation of the combustible mixture takes place. The walls of the chambers being heated also aid in this. Thus, the pipes 32, 34 are not subjected to any direct heat, and the oil while being carried therethrough is not converted into a gas, this being done beyond the pipes. As the oil while in the pipes is not heated and no gas converted therefrom, no carbon forms and thus is not deposited in the pipes. By having the fuel pipes in the air pipes, and the air being drawn in from the outside atmosphere, the fuel pipes are kept relatively cool at all times, and there is no opportunity for the oil to carbonize the pipes and block the same.

In Fig. 1, it will be noted that the air pipes 18, 19 are inclined downward toward the bottom walls of the chambers 25, these walls being formed, in the installation shown, by the base 10. These bottom walls are substantially flat and arranged substantially horizontal, so that the air when discharged into the chambers 25 strikes the bottom walls at a point in advance of the outlet passages 28. This results in giving the air a whirling action to vaporize oil more thoroughly and produce a more efficient gaseous mixture. The oil is of course atomized by the air passing over the discharge ends of the fuel pipes.

An oil burner of my invention is comparatively simple in its construction and operation and may be readily applied or installed in the fire-box of a steam boiler furnace, and will effectively produce the degree of heat required for generating steam in the boiler and supplant efficiently and economically the

use of coal or the like as fuel. The point of ignition of the combustible mixture is housed and no direct play of flame on the steam boiler is had, with advantages as apparent. 5 Other and further advantages will be apparent to those skilled in the art to which my invention appertains.

To support the fuel pipes 33, 34 in the air pipes, suitable hangers may be secured in 10 the air pipes for that purpose.

While I have shown and described herein in detail an oil burner constructed in accordance with my invention as applied to and used with a steam boiler furnace, it is to be 15 of course understood that the burner could be put to uses other than generating steam, and, further, it could be embodied in a furnace structure as a part of the original installation. Furthermore, it is to be understood that the various details of construction 20 of my burner and arrangement of parts as shown may be variously changed and modified without departing from the spirit and scope of my invention.

25 I claim as my invention:

1. In a structure of the character described, the combination with a main compartment having side and front walls, of means located in said compartment between 30 said side walls and spaced rearward from said front wall and forming a chamber smaller than the main compartment and opening into the latter, a liquid fuel supply pipe extending from said front wall to 35 said chamber and discharging into the latter toward and against one of the walls thereof, means for delivering air under pressure into said chamber from a point adjacent the discharge end of said fuel pipe for drawing 40 liquid fuel in said chamber and generating therein a combustible mixture for ignition in said chamber, and means in said compartment between said front wall and said chamber and surrounding said fuel pipe for 45 shielding the same from the direct action of the heat produced in said compartment.

2. In a structure of the character described, the combination with a main compartment having side and front walls, of 50 means located in said compartment between said side walls and spaced rearward from said front wall and forming a chamber smaller than the main compartment and opening into the latter, a liquid fuel supply 55 pipe extending from said front wall to said chamber and discharging into the latter toward and against one of the walls thereof, and an air pressure conduit surrounding said pipe between said front wall and said 60 chamber and opening into the latter about the discharge end of said pipe for drawing liquid fuel in said chamber and generating therein a combustible mixture for ignition in said chamber.

65 3. In a structure of the character de-

scribed, the combination with a main compartment having side and front walls, of means located in said compartment between said side walls and spaced rearward from said front wall and forming a chamber 70 smaller than the main compartment and opening into the latter, a liquid fuel supply pipe extending between said front wall and said chamber and discharging into the latter toward and against one of the walls thereof, a conduit extending between said front wall and said chamber and surrounding said pipe and opening into said chamber about the discharge end of said pipe, said conduit and said pipe extending through said front 75 wall to the outside of the same, and a blower connected with the other end of said conduit.

4. In a structure of the character described, the combination with a main compartment having front, side, and rear walls, of means located in said compartment between the side walls thereof and adjacent the rear wall of the same and forming with 80 said rear wall a chamber smaller than said 85 main compartment and opening into the latter toward one of said side walls, a liquid fuel supply pipe and an air pipe in said compartment and extending between said chamber and said front wall, said fuel pipe 90 discharging into said chamber, said air pipe surrounding the entire portion of the fuel pipe in said compartment and opening into said chamber about the discharge end of said fuel pipe and both discharging into 95 said chamber toward and against one of the walls thereof, and a blower located outside of said compartment and connected with 100 said air pipe.

5. A liquid fuel burner, comprising means 105 providing a chamber having an outlet at one end thereof and in one of the side walls of the same, a liquid fuel supply pipe opening into said chamber at the opposite end thereof and discharging toward the rear 110 wall of the same, and an air pressure conduit surrounding said pipe and opening into said chamber about the discharge end of 115 said pipe, said conduit being arranged at an inclination to one of the walls of said chamber for creating a whirling action to the air delivered into said chamber for generating a combustible mixture therein before its ignition in said chamber.

6. In a structure of the character described, the combination with a main compartment having side and front walls, of means located in said compartment between said side walls and spaced inward from said front wall and forming a plurality of chambers arranged side by side and each opening into said main compartment toward said side walls, liquid fuel supply pipes in said compartment, one for each chamber and extending 120 between the same and said front wall, 125

said pipes discharging into said chambers, and means for delivering air under pressure into said chambers from points adjacent the discharge ends of said pipes for drawing the liquid fuel into said chambers and generating therein combustible mixtures for ignition in said chambers.

7. In a structure of the character described, the combination with a main compartment having side and front walls, of means located in said compartment between the side walls thereof and spaced rearward from said front wall and forming two chambers arranged side by side and opening into 10 said compartment toward said side walls, liquid fuel supply pipes in said compartment, one for each chamber, and extending between the same and said front wall, said pipes discharging into said chambers, air 15 pressure pipes surrounding said fuel pipes and extending between said chambers and said front wall and outward through the latter, said air pipes opening into said chambers about the discharge ends of said fuel 20 pipes, and a blower mechanism exterior of said front wall and connected with said air pipes.

10. The combination with a furnace structure having a compartment formed by front, 75 side, and bottom walls, and a bridge wall, of a liquid fuel burner for producing heat in said compartment, comprising three upright walls built in said compartment on said bottom, two of said walls extending from the 80 front wall to a point short of said bridge wall, and the other wall being between said

8. The combination with a furnace structure having a compartment formed by front and side walls and a bridge wall, of a liquid fuel burner for producing heat in said compartment, comprising means providing a chamber within said compartment adjacent said bridge wall and opening into said compartment toward one of the side walls thereof, a liquid fuel supply pipe and a conduit extending into said compartment through the front wall thereof and discharging into said chamber toward said bridge wall, said conduit surrounding said pipe and opening into said chamber about the discharge end of said pipe, and a blower located outside of said furnace structure and connected with said conduit.

45 9. The combination with a furnace structure having a compartment formed by front, side, and bottom walls, and a bridge wall, of a liquid fuel burner for producing heat in said compartment, comprising three upright
50 walls built in said compartment on said bottom, two of said walls extending from the front wall to a point short of said bridge wall, and the other wall being between said two walls and extending from the bridge
55 wall toward the front wall to provide cham-

bers on opposite sides of said intermediate wall and opening into said compartment toward the respective side walls thereof, an arch over each chamber and forming the top wall thereof, two liquid fuel supply pipes 69 extending into said compartment through the front wall thereof and arranged between the upright walls extending from said front wall, said pipes discharging, one into each compartment adjacent the forward end of 6, said intermediate wall, two conduits extending into said compartment through the front wall thereof and arranged between said upright walls, said conduits opening, one into each of said chambers adjacent the discharge 76 ends of said pipes, and a blower connected with each conduit and located outside of said compartment.

10. The combination with a furnace structure having a compartment formed by front, 75 side, and bottom walls, and a bridge wall, of a liquid fuel burner for producing heat in said compartment, comprising three upright walls built in said compartment on said bottom, two of said walls extending from the 80 front wall to a point short of said bridge wall, and the other wall being between said two walls and extending from the bridge wall toward the front wall to provide chambers on opposite sides of said intermediate 85 wall and opening into said compartment toward the respective side walls thereof, an arch over each chamber and forming the top wall thereof, two liquid fuel supply pipes extending into said compartment through 90 the front wall thereof and arranged between the upright walls extending from said front wall, said pipes discharging, one into each compartment adjacent the forward end of said intermediate wall, two conduits extending into said compartment through the front wall thereof and arranged between said upright walls, said conduits surrounding said pipes and opening, one into each of said chambers about the discharge end of its respective pipe, a blower connected with each conduit and located outside of said compartment, a top wall extending across the two upright walls between which said conduits extend, and the compartment formed by said 100 upright and top walls being filled with sand. 105

In testimony that I claim the foregoing as my invention, I affix my signature, this 10th day of February, A. D., 1920.
